UNITED STATES PATENT OFFICE.

WENZEL J. DVORAK, OF SUNSET HEIGHTS, TEXAS.

CONCRETE CONSTRUCTION.

Application filed April 10, 1923. Serial No. 631,081.

To all whom it may concern:

Be it known that I, WENZEL J. DVORAK, citizen of Czechoslovakia, residing at Sunset Heights, in the county of Harris and 5 State of Texas, have invented certain new and useful Improvements in Concrete Constructions, of which the following is a specification.

This invention relates to new and useful 10 improvements in concrete construction, and has particular relation to construction which may be erected from concrete slabs. The invention embodies improvements in roof, ceiling and floor construction.

15 One object of the invention resides in the provision of an improved type of concrete construction wherein the slabs employed are precast and are tied to the supporting beams, or framework, in a novel way, said beams 20 being in the main, cast in place with a concrete like material while in plastic state.

With the above and other objects in view the invention has particular relation to certain novel features of construction, arrangement of parts, and use, an example of which is given in this specification and illustrated in the accompanying drawings, wherein:—

Figure 1 is a fragmentary plan view, partly in section, of a roof construction.

30 Figure 2 is a longitudinal sectional view thereof, taken on the line 2—2 of Figure 4.

Figure 3 is fragmentary transverse cross sectional view taken on the line 3—3 of Figure 1.

35 Figure 4 is a cross sectional view taken on the line 4—4 of Figure 1.

Figure 5 is a transverse sectional view taken on the line 5—5 of Figure 1.

Figure 6 is a fragmentary plan view, partly in section, of a type of flooring employed.

40 Figure 7 is a cross sectional view thereof taken on the line 7—7 of Figure 6.

Figure 8 is a longitudinal sectional view taken on the line 8—8 of Figure 6.

45 Figure 9 is a plan view, partly in section, of another type of flooring employed.

Figure 10 is a transverse sectional view taken on the line 10—10 of Figure 9.

Figure 11 is a longitudinal sectional view 50 taken on the line 11—11 of Figure 10.

Figure 12 shows an edge view of a section of ceiling.

Figure 13 shows a fragmentary plan view thereof, partly in section.

55 Figure 14 shows an enlarged plan view,

partly in section, of one of the ceiling slabs employed and,

Figure 15 shows a cross sectional view of said slab.

Referring now more particularly to the drawings, the numerals 1, 1 designate roof slabs which, in plan view, are of a general rectangular form. These slabs are precast and their upper surfaces are of any suitable configuration to represent shingles, tile or the like, as shown in Figure 1. The lower edge of each slab is designed to overlap the upper edge of the slab beneath it, as indicated in Figure 4, and these overlapping edges are suitably formed to interlock, one with the other, and the joint between them is preferably filled with pitch or tar 2, so as to form a water tight joint. The roof slabs are reinforced with lengthwise bars or rods 3, whose ends are formed with projecting loops as 4 which project beyond the ends of the slabs. These rods 3 may be wrapped, if desired, with reinforcing wire 5. In erecting the roof of the slabs 1 are first placed in their required position in which position they are held by suitable temporary frame work embodying forms as 6, which are to be later removed and in which the supporting beams for the roof are molded, said beams designated by the numerals 7 and 8. The beams 7 have the reinforcing rods 9 extending through them lengthwise and at suitable intervals these rods are surrounded by the loops or rings 10. The projecting loops 4 of the reinforcing rods 3 overlap in said form and the intermediate rods 9 extend through said overlapping loops as shown in Figures 1 and 3. The supporting beam 7 is then poured and when it sets around said reinforcing rods it securely ties 90 the adjacent ends of the slabs, 11 to it. The beams 7 alternate with the beams 8, illustrated in Figure 5. Each beam 8 has a deep groove 11 formed therein by the insertion of an inside V-shaped metal form 12, and when the beam is set this groove is filled with pitch or other water proofing material. This type of beam admits a certain amount of expansion and contraction. It is true that the expansion and contraction will cause the bottom of the beam to crack slightly, but the water proofing material will prevent any leakage. The reinforcing rods 9 of this beam on each side are surrounded by the rings 13, said rings being located at suitable inter- 100 105 110

vals apart, and the projecting loops 4, of the reinforcing rods 3 of the slabs are tied into said beam by the metal rods 9, thus forming a secure anchorage of the slabs to said beams 8.

When the beams have become set the forms 6 are then removed as they will no longer be necessary for supporting the structure.

In Figures 6, 7 and 8, the numeral 14 designates floor slabs which are rectangular in form, and the numeral 15 designates supporting beams therefor which are spaced apart and to which said slabs are anchored. These slabs have reinforcing rods 16 which project at each end, said projecting ends being formed into loops 17. These slabs are precast, but in constructing the floor they are laid in place and the supporting beams 15 are then poured while in plastic state. The 20 projecting ends 17 of the adjacent ends of the slabs overlap, as shown in the figures, and the tie rods 18, 18 are fitted through said overlapping loops as shown in Figures 7 and 8. These rods 18 also form reinforcing rods for the beams, 15, 15 and said beams also have the reinforcing rods 19, 19, said rods 18 and 19 being tied together by the rings or ties 20. These rods and ties are arranged in position before the 30 beams are poured and when the beams are poured they become set and embedded within them and the floor slabs thus securely tied to the floor beams.

The type of flooring shown in Figures 9, 35 10 and 11 is particularly adapted for porch flooring and consists of the rectangular slabs 21, and the end and side beams 22 and 23. The floor slabs 21 are spaced apart a short distance and have the reinforcing rods 24 whose ends project beyond the slabs and are formed with the loops 25. The end beams 22, 22 have the upper reinforcing rods 26, and the lower reinforcing rods 27 tied together by the ring like ties 28, and said upper rods pass through said loops 25. These beams 22 and 23 are poured while in plastic state after the floor slabs, which are precast, have been laid in place, and when the beams holding the floor slabs are securely tied to them.

In Figures 12, 13, 14 and 15 I have shown this type of construction as applied to ceiling wherein the numeral 29 designates the joist along the lower side of which is secured the rods 30 by means of suitable staples 31. The ceiling is formed of substantially rectangular slabs 32 which has reinforcing rods 33 embedded therein whose ends project and said projecting ends are secured to said rods to hold the slabs in place. The space between the ends of the slabs 32 is then filled with plastic concrete to cover up the rods 30 and the projecting ends of the rods 33 and to give a smooth finished surface to the ceiling.

What I claim is:—

1. A concrete construction formed of substantially rectangular concrete slabs, the adjacent edges of said slabs being correspondingly beveled so as to overlap and form a 70 comparatively smooth surface, lengthwise reinforcing bars embedded in the slabs, which project beyond the ends of the slabs, said projecting portions being formed into loops, concrete beams poured while in plastic state and supporting the adjacent ends of said slabs, reinforcing rods extending through the loops of the adjacent ends of the slabs, said loops and the rods extending through them being embedded in the 75 corresponding beams, alternative beams having deep, lengthwise grooves along their upper sides, water proofing material filling said grooves.

2. A concrete construction formed of substantially rectangular concrete slabs, the adjacent edges of said slabs being correspondingly beveled so as to overlap and form a comparatively smooth surface, lengthwise reinforcing bars embedded in the slabs, 80 which project beyond the ends of the slabs, said projecting portions being formed into loops, concrete beams poured while in plastic state and supporting the adjacent ends of said slabs, reinforcing rods extending through the loops of the adjacent ends of the slabs, said loops and the rods extending through them being embedded in the corresponding beams, alternative beams having deep, lengthwise grooves along their upper sides, water proofing material filling said 85 grooves, and rings embedded within said grooved slabs on opposite sides of the groove and surrounding the corresponding reinforcing rods thereof.

3. A concrete construction formed of substantially rectangular concrete slabs, the adjacent edges of said slabs being correspondingly beveled, said beveled portions overlapping, water proofing material between said overlapping edges, lengthwise reinforcing bars embedded in the slabs which project beyond the ends of the slabs, said projecting portions being formed into loops, concrete beams poured while in a plastic state, and supporting the adjacent ends of said slabs, reinforcing rods extending through the loops of the adjacent ends of the slabs, said loops and the rods extending through them being embedded in the corresponding beams, alternative beams having deep lengthwise grooves along their upper sides, and water proofing material filling said 105 grooves.

4. A concrete construction formed of substantially concrete slabs arranged adjacent to form comparatively smooth surface, lengthwise reinforcing bars embedded in the slabs which project beyond the ends of the slabs, said projecting portions being 110 120 125 130

formed into loops, the loops of adjacent ends of the slabs overlapping, reinforcing rods extending through said overlapping loops, concrete beams poured while in a plastic state around said loops and the rods projecting through the loops, said rods and loops reinforcing said beams, alternative beams having deep lengthwise grooves along their upper sides, and water proofing material filling said grooves.

5. A concrete construction including substantially rectangular slabs, reinforcing rods embedded in said slabs, and whose ends project therefrom, said projecting ends being formed into loops, the loops of adjacent slab ends overlapping, tie rods through said

overlapping loops, concrete beams poured while in a plastic state around said loops in tie rods, and supporting the ends of said slabs, said loops and tie rods forming reinforcements for said beams, ring like ties surrounding said tie rods and embedded in said beams, and reinforcing rods extending through said rings and being also embedded in said beams.

In testimony whereof I have signed my name to this specification in the presence of two subscribing witnesses.

WENZEL J. DVORAK.
